Patented Dec. 7, 1915

2 SHEETS—SHEET 2.

UNITED STATES PATENT OFFICE.

GUY B. WAITE, OF NEW YORK, N. Y.

ADJUSTABLE CENTERING FOR REINFORCED-CONCRETE FLOOR CONSTRUCTION.

1,163,188.

Specification of Letters Patent. Patented Dec. 7, 1915.

Application filed July 17, 1914. Serial No. 851,435.

To all whom it may concern:

Be it known that I, GUY B. WAITE, a citizen of the United States, and resident of the borough of Manhattan, city, county, 5 and State of New York, have invented certain new and useful Improvements in Adjustable Centerings for Reinforced-Concrete Floor Constructors, of which the following is a specification.

One of the main objects of this invention is to provide a centering for concrete floor constructions which may be readily adjusted longitudinally to the length of the supporting girders and which may be adjusted 15 transversely to adapt it to the spaces between the supporting girders.

Another object of the invention is to provide an adjustable centering which may be manufactured in quantities of standard 20 sizes and lengths and which may be readily assembled and adjusted to supporting girders of different lengths and to spaces of varying widths between the girders.

Another object of the invention is to construct the main portions of the centering of light sheet metal channels or troughs which may be adjusted longitudinally when adapting the centering to supporting girders and the space between said girders, said troughs 25 being adapted to be nested or packed one within the other when the centering is dismantled or "knocked down" for convenient transportation and storage.

There are other important objects and advantages of the invention all of which will more fully hereinafter appear.

In the drawings, Figure 1 is a sectional view of a portion of a reinforced concrete floor showing the centering hung on the 40 supporting girders and the concrete in position therein; Fig. 2 a sectional view on the line II—II of Fig. 1; Fig. 2^a a transverse sectional view on the line II^a—II^a of Fig. 1; Fig. 3 a plan view of the centering carried by the supporting girder; Fig. 4 a detail perspective sectional view of a portion of the centering which is supported on the girder; Fig. 5 a detail view of one of the loops by which the centering is hung to the 45 supporting girder; Fig. 6 an inverted perspective view of one of the transverse floor supporting members; and Fig. 7 a similar view of the other transverse floor supporting member.

Referring to the various parts by numerals, 1 designates the supporting girders; 2

the concrete molded around said girders and 3 the concrete floor.

To form the mold around each supporting girder I employ two sheet metal troughs 60 or channels 4, said troughs being open at their ends. These troughs are of any desired or suitable length and to stiffen the sides and the bottom thereof, longitudinally extending strengthening strips 5 are secured 65 to the outer side thereof, as shown clearly in Fig. 4. These strengthening strips are preferably of wood and extending around said reinforcing strips at suitable points along the length of the trough are straps or 70 yokes 6. The yokes and reinforcing straps are connected to the sheet metal troughs by means of wire loops 7 which are passed through holes in the sides and bottoms of the troughs and twisted around the outer 75 sides of the straps 6, as shown clearly in Figs. 1 and 4. These parts are secured together by any suitable means, that shown being twisted wire loops.

The troughs are suspended from the supporting girders by means of double or yoke-like loops 8 which are passed over the top of the girders, the arms 8^a extending down through apertures in the bottom of the trough as shown clearly in Figs. 1 and 3. 85 Through the lower ends of the arms 8^a and below the reinforcing strips 5 on the bottom of the trough is passed a supporting pin 9, as clearly shown in Fig. 1, the trough resting on said pin and being thereby supported by the loops 8. As many of these loops as are necessary may be used to support the troughs. When it is desired to detach the molds or troughs from the supporting girders it is only necessary to cut the 90 lower ends of the loops 8^a, thereby freeing the pins 9 after which the entire mold structure may be removed.

In order to adapt the troughs or molds to any length of supporting girder, extension 100 pieces 10 are used. These extension troughs or channels bridge the space between the adjoining open ends of the troughs 4 and are supported by said troughs. It will be readily understood that these extension or 105 bridge pieces may be extended any required length in order to bridge the space between the main sections 4 and that by reason of this construction the said troughs may be adjusted longitudinally to adapt them to 110 any length of supporting girder. It is manifest that as many of the main sections 4 of

the troughs may be used as are necessary; and that more than one of the bridge or extension sections 10 may be used if it be found necessary or desirable.

- 5 By using the reinforcing strips 5 and the strengthening yokes 6 very thin sheet metal may be used for the main and extension sections of the troughs or molds. It is also manifest that these mold sections may be 10 nested or packed one within the other when they are not in use, for convenience in transportation and storage. It is also manifest that the strengthening pieces 5 may be packed within the troughs so that the entire centering structure may be packed within a very small space and conveniently transported to the place of use or to a place of storage.

To bridge the space between the girder centering and to form the floor ^{or} port I 20 employ the adjustable or extensible floor centering 11. This centering consists of two inverted sheet metal channel sections 12 and 13, the section 13 sliding within the section 12, as clearly shown in Figs. 2 and 2a. 25 The section 12 is approximately twice as long as the section 13 and the latter section is adapted to slide within section 12. Secured to the depending side flanges of the section 13 are wooden brace pieces 14 which 30 extend considerably beyond the inner end section 13 and project into section 12, as shown clearly in Fig. 1. Rigidly secured to the section 1 is a strap or yoke 15 the lower end of which projects below the strengthening strips 14. Through the lower ends of 35 these straps and in position to engage the lower edges of the strengthening pieces 14, extend locking pins 16 which serve to lock the two adjustable sections together. It is 40 manifest that any weight placed upon the top of these interlocking sections will cause the inner end of the section 12 to bear strongly down on the top of the section 13, thereby preventing any concrete lodging between the two sections. It is also manifest 45 that the two sections may be adjusted to fit any space between the supporting girders, this being limited, however, to the extreme extension of the two parts or sections. The 50 outer ends of the sections 12 and 13 of the floor centering are provided with hooks 17 which are adapted to be engaged over the strengthening strips 5, or other supporting means carried by the trough sections 4 or 55 the extension sections 10.

The sections 12 and 13 form supporting members which are arranged side by side, a suitable space being left between adjoining members. This space is preferably bridged 60 by a flat sheet metal plate 18, as shown clearly in Fig. 2. The sections 12 and 13 are preferably formed of sheet metal and when adjusted to their smallest dimensions they may be readily packed for transportation 65 and storage.

From the foregoing it is manifest that I provide an adjustable centering of which the main members are formed of sheet metal of light construction adapted to be reduced to small dimensions for transportation and storage. It is also manifest that I provide a centering which is adjustable longitudinally to adapt it for supporting girders of various lengths; and is also adjustable transversely to adapt it to fit between girders located different distances apart. It is also clear that the parts of the centering may be manufactured in standard sizes and these may be assembled and adjusted at the place of use.

The structure shown in the drawings and described herein, but not claimed, is embodied in my copending application Serial No. 851,486, filed January 17, 1914.

What I claim is:

1. A centering for a concrete floor construction comprising a sectional adjustable girder centering consisting of a pair of main trough-like sheet metal mold sections, means for suspending said mold sections from a girder, a trough-like extension section bridging the space between and supported by said main mold sections, a sectional adjustable floor centering means consisting of two inverted channel sections slideable one within the other to bridge the space between the girder centering, means at the outer ends of said floor channel sections to support said sections on the girder centering, means for interlocking the inner ends of the channel sections to support said inner ends.

2. A centering for a concrete floor construction comprising a sectional adjustable girder centering consisting of a pair of main trough-like sheet metal mold sections, means for suspending said mold sections from a girder, a trough-like extension section bridging the space between and supported by said main mold sections, a sectional adjustable floor centering means consisting of two inverted channel sections slideable one within the other to bridge the space between the girder centering, means at the outer ends of said channel sections to support said sections on the girder centering, means for interlocking the inner ends of the channel sections to support said inner ends, and bridging plates extending across the space between the floor centering and supported by said centering.

3. A centering for a concrete floor construction comprising a sectional adjustable girder centering consisting of a pair of trough-like sheet metal main mold sections, means for suspending said main sections from a girder, a trough-like extension section bridging the space between the main mold sections, longitudinally extending bracing strips on the outer side of each of the main mold sections near the upper edges

thereof, a sectional adjustable floor centering consisting of two inverted channel sections slidable one within the other to bridge the space between the girder centering, 5 means at the outer ends of these channel sections to engage the bracing strips on the girder centering to support said floor centering, and means for interlocking the inner ends of the channel sections to support 10 them in proper alignment.

4. A sectional adjustable girder centering for concrete floor construction comprising a pair of main trough-like sheet metal mold sections, a series of longitudinally extending 15 bracing strips on the outer side of said sections, a series of reinforcing yokes extending around said sections outside of the bracing strips, tying bands passing through the walls of the mold and securing the bracing 20 strips and the yokes directly to the walls of the mold section, a trough-like extension section bridging the space between and supported by the main mold sections.

5. A centering for concrete floor construction comprising two inverted sheet metal channel sections adapted to slide on each other, one of said sections carrying reinforcing bars which project into the other section, means carried by the said other 30 section for engaging the said reinforcing bars and thereby interlocking the two sections, and means at the outer ends of the slidable channel sections to support said centering.

35 6. A centering for concrete floor construction comprising sectional adjustable supporting elements consisting of two inverted channel sections having a top and depending sides, one of said channel sections fitting 40 and sliding within the other, the inner section having longitudinally extending brace pieces secured to the inner surface of each of its depending flanges, said brace pieces projecting a suitable distance beyond the 45 inner end of the said section, depending arms secured to the under side of the outer section, pins projecting through said arms

and forming supports for the projecting ends of the brace pieces carried by the other section, and means at the outer end of each 50 of said slidable sections for supporting said sections in position.

7. A centering for a concrete floor construction comprising a sectional adjustable girder centering consisting of a pair of 55 main trough-like sheet metal mold sections, means for suspending said main mold sections from a girder, a trough-like extension section bridging the space between and supported by said main mold sections, a sectional floor construction comprising two 60 sheet metal channel sections adapted to slide on each other, one of said sections carrying reinforcing bars projecting into the other section, means carried by the said other 65 section for engaging the said reinforcing bars and thereby interlocking the two sections, and means at the outer ends of the slidable sections of the floor centering to engage the girder centering whereby the 70 floor centering will be supported from the girder centering.

8. A girder centering comprising a pair of main trough-like sheet metal mold sections, a series of longitudinally extending 75 bracing strips on the outer side of each of said main mold sections, a reinforcing yoke around said mold section outside of the bracing strips, ties passing through the walls of the mold and securing the reinforcing strips and the reinforcing yokes directly to the mold, loops adapted to be suspended from a girder and to pass through the bottom of the main mold sections, supporting pins passing through said loops below the mold sections, and a trough-like extension section bridging the space between and supported by the main mold sections.

In testimony whereof I hereunto affix my signature in the presence of two witnesses. 90
